SHELF OR STEP DISPLAY

Henry Ziemmerman, Chicago, Ill., assignor to
Chicago Cardboard Company, Chicago, Ill., a
corporation of Illinois

Application July 6, 1931, Serial No. 548,970

17 Claims. (Cl. 211—156)

This invention relates in general to a folding display stand for counter, window or other advertising purposes and has more particular reference to a folding step display which collapses and folds to compact form for storing and shipping.

One of the principal objects of the invention is in the provision of a display of this kind which is angular in form, simulating a step corner comprising a plurality of steps.

A further object of the invention is in the provision of a new and improved display stand which folds and unfolds easily and readily without danger of breaking or folding the parts incorrectly and with a locking device for holding the parts in distended position.

A further object of the invention is in the provision of a multiple step display in which the step portions are foldable upwardly upon the main supporting plate and which unfold downwardly to step form when the plate is unfolded.

A still further object of the invention is in the provision of a step display having flat extensions at the bottom of the lowermost step.

Other objects of the invention will appear hereinafter, the accompanying drawings illustrating a preferred form of the invention.

In the drawings; Figure 1 is a perspective of one form of the invention in distended position, with parts broken away for clearness;

Figure 2 is a side elevation of the display in folded condition;

Figure 3 is a section taken on the line 3—3 of Figure 1;

Figure 4 illustrates a modification. Figs. 5 and 6 show blanks of which the structure of Fig. 1 is made; and Fig. 7 shows the blank for the structure of Fig. 4.

It is not difficult to make a display stand with steps which unfold from an upright back plate, but the present invention relates to a novel form of step display in which the steps are angular, representing a corner of a step construction with a supporting back or panel at the rear of the steps. Furthermore, in folding the steps of an angular step display, the step portions are not only foldable together but they must also collapse upon each other and upon a dividing line common to all of the steps so that they will fold compactly upon the supporting plate for conveniently storing and shipping the displays.

Referring now more particularly to the drawings, a main plate or panel has upper side display portions 5 separated by a score line 6 about which they are foldable rearwardly and the lower

portions of the panel have supports 7 cut from the lower edge 8 of the main plate and connected thereto at the fold line 9 with slits at the edges below the upper display portions 5 adapting the supports 7 to fold at an angle to the upper display portion when the stand is in extended position.

Attached to the main panel by being adhesively cemented or otherwise fastened to the upper edge of each support is an angular step construction 10 which may also be cut from a single piece of sheet material and comprises a number of riser 11 and tread 12 portions having a fold line 13 at the angle of the step coinciding when folded with the fold line 6 of the main plate, the step construction being formed by providing slits 14 in the upper tread portions with a flap 15 in the riser portions which is secured to the adjacent riser portion so that when distended the steps will preferably be right angular in cross section 15 and the corner or angular step portion may either be a right angle or more or less than a right angle. In the form shown in Figures 1 and 4, the angular step portion is greater than a right angle. Attached to the lower edge of the lower step riser 20 11 are floor plates 16 which may be folded inwardly, or outwardly as shown, these plates adding to the decorative value of the display and also making it more stable when in use.

The upper step riser 11 at each side of the angular corner is fixedly cemented to the upper portion of the corresponding main plate support 7 as indicated by stippling 7a in Fig. 5. These supports 7 bend at the fold lines 9 in extending the step structure at an angle to the main plate 35 5 as shown in Fig. 1, and together with fold lines 17 and 18 adapt the steps to fold upwardly upon themselves and upon the main plate or panel when the parts are collapsed as shown in Figure 2.

To the top of one side of the upper step riser 40 is pivoted a locking flap 20 which is angular in form, having at its rear edge a projection 21 to engage and lock in a recess 22 at the center of the main plate or panel to distend the side portions 5 thereof, and hold them distended in the same plane. This locking flap is disengaged by reversing the locking operation which releases the main plate for folding the sides of it rearwardly together which also causes or enables the steps to be folded together upwardly, as shown, 45 or downwardly, the upward folding being preferred as it is more compact.

In unfolding this display stand, it is necessary only to partially separate or unfold the side portions of the main plate or panel which will 50

allow the steps to unfold and assume a right angle position with the lower edges engaging and resting upon the floor and with the standards or supports 7 holding the display stand in upright position.

A similar angular step display, as shown in Figure 4, may be made of a single sheet of material, a section or sections of which are cut out from the upper edge with corresponding step or shelf portions 27 and riser portions 28 having score and fold lines 29 and 30 adapting them to collapse upwardly (or downwardly) upon themselves and the side portions to fold rearwardly. This form may also have the floor extension plates 31 and 32 hinged to the lower edges of the step sections, and may be used separately or with a background or rear panel plate, as shown.

In making a display of this kind the shelf or step portion is made from a single sheet of cardboard or the like, by cutting out an angularly notched portion for each corner and then connecting the adjacent riser portions together by means of an extension such as flap 15 or to the sides of the supporting plate. With this construction the steps or supports present a neat and unitary appearance and by carefully cutting out the removed portions, the angular portions will fit closely together. Thus the supporting portion and the display portion need be made only of two separate sheet parts which are cut, scored and secured together. It is possible also to make similar structures with a larger number of parts by securing them together but usually this is neither as satisfactory in appearance nor as economical in construction.

In these angular shelf or step displays the steps fold upwardly or downwardly together and the sections of the same step fold upon themselves and together with the portions of the supporting plates so that in the collapsed or folded condition the structure is substantially flat and occupies minimum space for storage and shipment. As the parts naturally assume their supporting and display positions in unfolding there is no difficulty in properly setting up the display for use.

I claim:

1. An angular shelf or step corner unit formed of a single sheet of material having an angular section cut out and scored to form step and riser portions and corresponding riser portions permanently secured together to form an angular corner support, and having score and fold lines adapting the step and risers at one side of the corner to fold together upon themselves and the folded parts at opposite sides of the corner to fold together about the corner in collapsing.

2. A shelf or step unit angular in horizontal section, comprising a scored and folded sheet having a section cut out from the upper edge to form step and riser portions and corresponding riser portions permanently secured together to form the projecting corner of a connected step unit, the side portions of which are adapted to fold together in overlying relation and the two folded sides to fold together about the angular corner in collapsing to compact form.

3. A folding shelf or step corner unit in accordance with claim 2 and a foldable background plate having two hinged sections to which the corresponding side portions of the unit are attached so that in folding the plate the step portions are also folded upon themselves and collapsed against the outside of the folded plate.

4. A shelf or step display having an upright plate with side sections to fold upon a vertical

axis, and a permanent angular corner step unit having adjacent hinged side portions connected to the corresponding section of the plate and the steps thereof being connected together and the side portions being foldable about horizontal fold lines against the outer faces of the plate when the plate is folded to collapse the display.

5. A display having an upright plate unit for a background scored to fold rearwardly upon itself, and an angular supporting step corner having side portions each connected to corresponding portions of the unit and each side portion comprising connected steps and risers scored to fold together upon the unit, the said step and riser portions being hinged together at the corner and unfolding by gravity to assume supporting position when the plate unit is placed upright and is unfolded.

6. A display having an upright plate for a background and to rest upon its lower end, a multiple step corner unit comprising side sections secured to the plate and each section having transverse scores forming connected step and riser portions adapting the step and riser portions to fold horizontally upon each other and side portions folding together about the corner and against the plate in collapsing.

7. A display having a single supporting plate with side folding parts, an angular multiple step corner structure comprising connected sections hinged to the plate intermediate the top and bottom and the bottom of each section adapted to rest upon the same support as the plate, and each section having horizontal and vertical score and fold lines forming connected steps and risers to collapse together and to fold with and against the outer sides of the plate when the said sides are folded.

8. A display having a single vertically scored upright plate flat when set up to rest upon one end, angular multiple corner steps comprising a single sheet having portions hinged to the plate and the portions scored horizontally to form connected steps and risers foldable upon each other to collapse together in overlying relation and to fold about the corner and against the plate in folding the display.

9. A step display comprising an upright plate, an angular multiple step corner support unit formed of a single sheet with connected side sections forming the corner hinged thereon and the supports scored transversely to form connected steps and risers foldable upon each other in collapsing, and a locking portion at the top of the unit having means to engage the plate for holding the display extended.

10. A step display comprising an upright plate having parts foldable together for collapsing, an angular step corner unit comprising sections connected thereto at their upper ends with transverse scores forming steps foldable together horizontally and vertically upon said plate parts in collapsing, the plate having an opening and the unit having a locking tab forming the top step with a projection to engage in the opening to prevent the parts from collapsing.

11. A step or shelf display comprising an upright plate having side portions foldable rearwardly for collapsing, an angular multiple support structure secured to the sides and unfolding in succession therefrom, and a locking member at the top conforming to the angular shape of the supports and having a rear portion to engage the plate and prevent it from folding until the locking portion is raised.

12. A shelf or step display comprising an upright plate having hinged sections with lower portions adapted to support it, the lower portions being bendable relative to the upper display portions of the plate, lower angular supports foldable upon and hinged to the lower supporting portions of the plate and collapsing together with the side portions of the plate in folding the parts, and a locking member hinged to the supporting parts having an angular front conforming to the lower portions of the supports and having a straight rear portion to engage the display portions of the plate to prevent it from collapsing. 5
13. A shelf or step display of the class described, comprising an upright plate having sides bendable rearwardly together and each side having a lower angularly disposed portion upon which the plate stands, an angular supporting unit comprising a single plate with angular upper cut-outs foldable to make steps or shelves and secured together and to the angular sides of the plate so that they will unfold therefrom when the plate parts are unfolded and will collapse together with the sides of the plate when the plate is folded. 10
14. In an angular corner step folding display, a single piece of sheet material having a section cut out of its upper edge and the side portions scored transversely to form connected steps and risers with corresponding riser portions thereof secured permanently together to form steps angular in horizontal section, and a floor display flap hinged to the lower edge of each side portion and adapted to extend in front thereof, the step and flat portions at the sides of the corner collapsing together upon themselves and the sides folding 15
15. A step or shelf display comprising an upright plate having hinged sections with lower portions adapted to support it, the upper portions being bendable relatively to the said lower portions, lower angular supports foldable upon and hinged at the upper portions to the lower supporting portions of the plate, and scored transversely to collapse together with the side portions of the plate in folding the parts, the angular supports being also foldable at the corner in collapsing with the hinged sections of the upright plate. 20
16. A step or shelf display comprising an upright plate having side portions foldable rearwardly together for collapsing, an angular multiple support secured to the sides and scored transversely for unfolding in succession therefrom, the angular corners having the risers permanently secured together but hinged at the corner to form a collapsible projecting multiple step corner extending in front of the plate when the structure is unfolded. 25
17. A shelf or step display comprising an upright plate having portions foldable together about a vertical fold line, an angular multiple support structure comprising steps and risers connected together by horizontal fold lines and extending angularly in front of the upright plate, corresponding risers being connected at the corner for folding the sections of the multiple support structure about a vertical axis with the upright plate in collapsing, the steps and risers at each side of the corner folding together when the upright plate is folded. 30
